UNITED STATES PATENT OFFICE.

DAVID LA TREMOUILLE AND HULDEGE GEORGE LA TREMOUILLE, OF
OSWEGO, NEW YORK.

POISON-BOTTLE.

No. 853,887.

Specification of Letters Patent.

Patented May 14, 1907.

Application filed November 21, 1905. Serial No. 288,474.

To all whom it may concern:

Be it known that we, DAVID LA TREMOUILLE and HULDEGE GEORGE LA TREMOUILLE, citizens of the United States of America, residing at Oswego, in the county of Oswego and State of New York, have invented new and useful Improvements in Poison-Bottles, of which the following is a specification.

Our invention relates to poison bottles, and its primary object is to provide a novel and highly useful device of this character which may be readily distinguished either visually or when grasped from other bottles to prevent the accidental taking of poison.

With the above and other objects in view, the invention consists of the construction, combination and arrangement of parts hereinafter fully described, claimed and illustrated in the accompanying drawings, wherein:

Figure 1 is a side elevation of a poison bottle constructed in accordance with our invention. Fig. 2 is a central vertical section. Fig. 3 is a bottom plan, and Fig. 4 is a top plan.

Referring to the drawings by reference numerals, 1 designates the body, 2 the neck and 3 the bottom of a poison bottle constructed in accordance with our invention. The body 30 of the bottle has a pronounced elongated formation, and is preferably rectangular in cross section. The body is formed to provide an angular recess 4 which is located at a point intermediate its ends, and which extends fully around the body. A bottle having a body of pronounced elongated formation, rectangular in cross section and provided with a recess may be readily distinguished when grasped, or visually distinguished when it is in an upright position upon a shelf. The neck of the bottle is comparatively short, rectangular in cross section and provided with a rectangular marginal flange 5, and its bottom is provided with a 45 rectangular groove. A bottle provided with a neck of this construction and with a rec-

tangular groove in its bottom possesses such peculiar characteristics that it may be readily distinguished visually from other bottles when it occupies such a position upon a shelf 50 that either its neck or bottom is pointed outward.

It should be apparent from the above description taken in connection with the accompanying drawings, that we provide a 55 poison bottle which possesses such peculiar characteristics that it may be easily and quickly distinguished when grasped or visually from other bottles, regardless of what position it occupies upon a shelf, and that 60 thereby it is impossible to accidentally take a harmful medicine.

From the foregoing description taken in connection with the accompanying drawings, the construction and mode of operation of 65 the invention should be understood without a further extended description.

Changes in the form, proportions and minor details of construction may be made within the scope of the invention without departing from the spirit or sacrificing any of the advantages thereof.

Having fully described and illustrated our invention, what we claim is:

The herein described bottle having a rectangular body portion provided with an angular recess upon the outer wall surrounding the body portion, and an inwardly extending V-shaped rib, the material of the body portion being of equal thickness throughout, a 75 short and rectangular neck portion provided with a rectangular marginal flange, and said bottle having a rectangular groove in the bottom thereof, essentially as described.

In testimony whereof, we affix our signatures in presence of two witnesses.

DAVID LA TREMOUILLE.

HULDEGE GEORGE LA TREMOUILLE.
